UNITED STATES PATENT OFFICE.

FREDERICK HACHMANN, OF ST. LOUIS, MISSOURI, ASSIGNOR, BY MESNE ASSIGNMENTS, TO NATIONAL METAL DIE MOLD COMPANY, OF ST. LOUIS, MISSOURI, A CORPORATION OF MISSOURI.

CASTING-MOLD.

1,334,030.

Specification of Letters Patent. Patented Mar. 16, 1920.

Application filed July 5, 1918. Serial No. 243,450.

To all whom it may concern:

Be it known that I, FREDERICK HACHMANN, a citizen of the United States, residing at the city of St. Louis and State of Missouri, have invented a new and useful Casting-Mold, of which the following is a specification.

This invention relates to casting molds.

An object of the invention is to provide a casting mold of novel construction for venting the gases therefrom below the level of the material in the mold.

Another object is to provide a casting mold in which the mold cavity is formed in a non-metallic material and which has an inlet passage or gate formed through said material which will not chill the molten metal passing into the mold cavity.

Another object is to provide a casting mold having an inlet passage or gate opening through the bottom wall of the mold which is composed of non-metallic substance or material which will not chill the molten metal being poured into the mold, and a series of venting passages through the mold wall for venting the gases from the mold cavity below the level of the material in the mold cavity.

A further object of the invention is to provide a mold having the novel and advantageous features of construction herein-after described and claimed.

Figure 1 is a side elevation of my improved mold.

Fig. 2 is an elevation looking toward another side thereof.

Fig. 3 is an elevation of one part of the mold, illustrating the mold cavities, the gates for conducting the material into the mold cavities and the venting passages for conducting the gases from the mold cavities during the operation of casting.

Fig. 4 is a view illustrating in detached relation the parts forming one of the frames of the mold.

Fig. 5 is a plan view of the mold.

Fig. 6 is a vertical sectional view on the line 6—6 of Fig. 1.

Fig. 7 is a cross sectional view on the line 7—7 of Fig. 1.

Fig. 8 is a view of one of the castings made in the specific form of mold illustrated.

In the specific form of mold shown there

are two mold cavities 1 formed in a mold body composed of several sections of non-metallic material such, for instance, as soap stone or saponite having matching recesses therein and placed together so that the recesses form the desired mold cavities. Although the mold cavities shown are of peculiar shape for casting articles of the form shown in Fig. 8, it will be understood that the invention is not restricted to casting articles of any particular shape; nor is the invention confined to a mold having two mold cavities, for it is perfectly plain that the invention is not restricted to these details. From each mold cavity several series of venting passages 2 extend obliquely upwardly and outwardly for conducting the gases from the mold cavity from below the level of the material being cast during the casting operation, and into outlet passages 2'. As shown these passages may be composed of grooves formed in the contacting faces of the sections of material forming the mold cavity.

The bottom 3 of the mold is also composed, preferably of sections of non-metallic substance such as soap stone or saponite having gates or passages 4 opening into the lower ends of the mold cavities for delivering the molten metal into the lower ends of the cavities; and said passages 4 receive the molten metal from a passage 5 having communication with a hopper 6 in which the molten metal is poured.

The top 7 of the mold is also composed of sections of soap stone or saponite having relatively large openings 8 in communication with the upper ends of the mold cavities.

The mold body is thus composed of several sections which, when assembled and held together in proper relation, form mold cavities having inlet passages for conducting the molten metal into the cavities and venting passages for the escape of the gases. The mold sections are held together in an appropriate metallic frame provided for that purpose. The frame shown is of the built-up type composed of a box-like bottom member 9 for receiving and retaining the bottom 3 of the mold; two matching side members 10 detachably secured to the bottom member; and two top members 11 detachably secured to the side members. As shown the side

members are secured to the bottom of the frame by pins or lugs 12 on the bottom members engaging in holes in the side members; and by screws 13 passing through portions of the bottom member and engaging with said side members. Also, there are pins 14 on one of the side members engaging in holes 15 on the other side member to strengthen the frame. The top members 11 10 of the frame are similarly secured to the side members by pins or lugs 16 on the top members engaging in holes in the side members and by screws 17 passing through parts of the top members and engaging in the side members of the frame. The sectional frame thus constructed is held together by clamps composed of brackets 18 embracing the frame as shown in Fig. 5 and equipped with clamping devices 19 in the form of screws 20 operable to press the frame sections together and being releasable to permit separation of the mold for removal of the articles cast, or other purposes.

Layers 20 of asbestos or the like are 25 placed between the side of the built-up mold and the sides of the frame. It is desirable to employ some material having the elastic and heat non-conducting qualities of asbestos in order to permit proper relative expansion and contraction and to compensate for any variation since the coefficients of expansion and contraction of the non-metallic substances forming the mold body are different from the coefficients of expansion and contraction of the metallic frame.

As shown in Fig. 7, the sections of non-metallic material forming the mold body may be formed with tongues or projections 21 to engage in appropriate channels in the 30 adjacent parts of the frame in order to assist in holding the parts properly together.

A mold of this character produces castings of great density and tensile strength and free of porosity and is therefore highly 45 useful for a variety of purposes. In mentioning soap stone or saponite as appropriate material from which the mold body may be constructed, it will be understood that I do not restrict myself to the use of such substances only, since there may be a variety of 50 appropriate substances which will not chill the molten metal passing into the mold cavity before the mold cavity is filled, but which will permit the mold cavity to be 55 completely filled before the advance portion of the material begins to harden or solidify.

I claim:

1. A casting mold composed of separable 60 sections of lithic material arranged in side and superimposed relation and forming a mold cavity between them adapted to form a casting and having an open upper end, means for holding the sections of lithic material in side by side and superimposed 65 relation and a passage opening into the bot-

tom of the mold cavity through one of the walls thereof, for delivering molten material into the bottom of the cavity.

2. A casting mold, comprising a mold body composed of separable sections of lithic material arranged in side by side and superimposed relation and forming a mold cavity between them adapted to form a casting and having an open upper end, means for holding the sections of lithic material side by side, means for holding the sections of lithic material in superimposed relation, and a passage opening into the bottom of the mold cavity through one of the walls thereof, for delivering molten material into the bottom of the mold cavity.

3. A casting mold, comprising a mold body composed of separable sections of lithic material arranged side by side and forming a mold cavity between them adapted to form a casting and having an open upper end, a passage in the lithic material opening into the bottom of the mold cavity, and a passage extending downwardly from the top of the mold body for delivering the molten material into said first-named passage.

4. A casting mold, comprising a mold body composed of separable sections of lithic material arranged side by side and forming a mold cavity between them adapted to form a casting and having an open upper end, a passage in the lithic material opening concentrically into the mold cavity through the bottom wall thereof, and a passage extending downwardly from the top of the mold cavity into said first-named passage for delivering the molten material into the first-named passage.

5. A casting mold, comprising a mold body composed of sections of lithic material arranged side by side, and forming a series of mold cavities between them adapted to form separate castings and having an open upper end, a passage in the lithic material opening into the bottom thereof each of said cavities, and a passage through the lithic material for delivering molten material into the first-named passage.

6. A casting mold, comprising a mold body composed of separable sections of lithic material arranged side by side and in superimposed relation forming a mold, a series of cavities between them adapted to form separate castings, a passage in the lithic material opening into said cavities, a passage for delivering molten material into the first-named passage, and venting passages through the walls of said cavities adapted to insure escape of the gases from 125 said cavities during the casting operation.

7. A casting mold, comprising a mold body composed of separable sections of lithic material arranged in side by side and superimposed relation and forming a series 130

of mold cavities between them adapted to form separate castings, a passage in the mold body below said cavities and opening into the bottoms of said cavities, a passage 5 extending downwardly through the mold body from the upper end thereof opening into said first-named passage for delivering molten material into the first-named passage, and venting passages extending upwardly and outwardly from said cavities through the mold body adapted to insure escape of the gases from said cavities during the casting operation.

8. A casting mold, composed of separable 15 sections of lithic material, each of said separable sections being composed of a plurality of superimposed members; means for holding the members of each section in superimposed relation; means for holding the 20 separable sections side by side to form a mold cavity; and a passage for delivering molten material into the bottom of the mold cavity.

9. A casting mold, comprising a mold 25 body composed of separable sections of lithic material, each of said sections being composed of a plurality of superimposed members; means for holding the members of each section in superimposed relation; 30 means for holding the separable sections in side by side relation to form a mold cavity between them adapted to form a casting; venting passages extending upwardly and outwardly from the mold cavity adapted to 35 insure escape of the gases during the casting

operation; and a passage between said sections for delivering molten material into the bottom of the mold cavity.

10. A casting mold, comprising a mold body composed of separable sections, each 40 of said sections being composed of a number of superimposed members; means for holding the members of each section in superimposed relation; means for holding said sections in side by side relation to form a plurality of mold cavities between them adapted 45 to form separate castings; a passage for conducting molten material to a point near the bottom of the mold body; and branches from said passage for conducting molten 50 material into said mold cavities respectively.

11. A casting mold, comprising a mold body composed of separable sections, each of said sections being composed of a number of superimposed members; means for holding the members of each section in superimposed relation; means for holding said sections in side by side relation to form a plurality of mold cavities between them adapted to form separate castings; a passage 60 for conducting molten material to a point near the bottom of the mold body; branches from said passage for conducting molten material into said mold cavities respectively; and venting passages extending upwardly and outwardly from said mold cavities 65 respectively adapted to insure escape of the gases from said cavities during the casting operation.

FREDERICK HACHMANN.
